CONDENSER CONSTRUCTION

Application filed May 23, 1930. Serial No. 455,071.

This invention relates to electric condenser construction.

One of the objects of this invention is to provide a simple, practical and efficient electric condenser. Another object is to provide an electric condenser for operation at high voltages and to minimize insulation difficulties. Another object is to provide an electric condenser of the above-mentioned character in which a high capacity per unit volume may be achieved in a thoroughly dependable and inexpensive manner. Another object is to provide an electric condenser capable of long-continued use and in which the possibility of break-down is greatly minimized. Other objects will be in part obvious or in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawings in which is shown one of various possible embodiments of my invention,

Figure 1 is a vertical central sectional view of the assembled condenser construction, certain parts being indicated diagrammatically,

Figure 2 is a horizontal sectional view, as seen along the line 2-2 of Figure 1, and

Figure 3 is a detached vertical sectional view, like that of Figure 1 but fragmentary, on an enlarged scale, showing a possible mechanical connection between certain of the solid dielectric parts of Figure 1.

Similar reference characters refer to similar parts throughout the several views of the drawings.

Referring now more particularly to Figure 1, there is shown at 10 a tank or container preferably made of heavy steel so as to withstand substantial pressures; this container is preferably of generally cylindrical shape and is preferably a pressed steel tank, having therefore an integrally formed end 11 and being provided with an end mem-

ber 12 adapted for closing and sealing the container.

The upper end member 11 is provided substantially centrally thereof with a high voltage bushing or terminal 13 which may be of any suitable construction for passing a high voltage conductor from the inside of the casing 10 to the exterior thereof. Resting against and secured to the end member 11 is a metal member 14 provided with a suitable number of arms, shown in Figure 2 as four in number, the arms extending radially and having a length substantially equal to the radius of the tank 10. These arms are slotted on their lower faces as at 15, 16 and 17, the slots 15 extending along a circle of a radius equivalent to that of a tube 18 of solid dielectric material, such as Bakelite or Dilecto so that the upper end of the tube 18 may be seated in the four innermost slots 16 on the arms of the member 14.

The slots 16 are similarly shaped to lie on a circle so that the upper end of a tube 19 of solid dielectric material, of greater diameter than that of the tube 18, may be seated in the slots 16 and the two tubes thus held concentrically. The slots 17 lie along a circle of still greater radius and form seats for the upper end of a tube 20 of similar solid dielectric material and of still greater diameter.

Each solid dielectric tube, illustratively three in number, though it is to be understood that more or less than three may be employed, supports a condenser stack, each stack being made up of spaced and insulated plate members and being, in so far as certain features of my invention are concerned, of any suitable construction, but preferably these stacks are made up of metal foil plates alternated with a suitable solid dielectric material in sheet form, such as paper.

Considering first the condenser stack 23 associated with the outermost tube 20, the metal foil plate members and the interposed paper insulation are washer or torus-shaped and are alternately strung onto the solid dielectric tube 20, the completed stack 23 being supported at its upper and lower ends by

washers 21 and 22, respectively, made of solid dielectric material and suitably secured to the solid dielectric tube 20, as by pinning thereto. In Figure 3 I have shown on an enlarged scale a pin 50 passing through the solid dielectric tube 20 and into the washer 21, as illustrative of a possible way of securing together these as well as the insulating tubes and other insulating washers mentioned hereinafter.

The inside diameters of these washer-shaped condenser elements are substantially equal to the outside diameter of the solid dielectric tube support 20 but the outside diameters thereof progressively decrease from one end of the stack to the other, illustratively in Figure 1, from the lower end of the stack 23 to the upper end, thus to provide a spacing between the stack 23 and the interior side wall of the casing 10 that progressively increases in an upward direction.

The solid dielectric tube 19 has strung thereupon a condenser stack 24 of generally similar construction, the latter being held between upper and lower washers 25 and 26 of solid dielectric material, suitably secured to the supporting tube 19. The inside diameters of the condenser elements of the stack 24 are uniform so that the washer-shaped elements fit snugly about the tube 19, but the outside diameters of these elements progressively diminish in a direction from the upper end of the stack 24 to the lower end thereof, thus to provide a spacing between the stack 24 and the surrounding stack 23 that increases in a downward direction, for a purpose more clearly described hereinafter.

The innermost tube 18 also supports a condenser stack 27, held between upper and lower washers 28 and 29 and having elements of an outside diameter increasing progressively in a direction from the upper end of the stack 27 to the lower end thereof, thus to provide a spacing between the stacks 27 and 24 that increases radially from one end of the stack toward the other.

The lower ends of the solid dielectric tubes 18, 19 and 20 are received in slots 30, 31 and 32 formed in a member 33 substantially similar in construction to the member 14 above-described, the slotted member 33 being secured to the inside face of the closure member 12, the latter being welded, or otherwise suitably secured to the container 10, as is indicated at 34.

Thus the several condenser stacks are arranged concentrically with respect to each other as well as with respect to the cylindrical tank 10, all as will be clear particularly from Figure 2.

The condenser elements of each condenser stack may be connected together in any suitable manner, but preferably each stack is sub-divided into sections, the sections being connected in series but the condenser units

or elements within a section being preferably connected in parallel. Preferably also the capacities of the different sections are the same.

Thus by way of illustration, I have shown the condenser stack 23 made up of eight sections 23^a, 23^b, 23^c, etc., the axial length of the successive sections increasing as their individual outside diameters, and hence the areas of their individual plates, decrease, in order that the capacities of all of the sections be the same.

The individual condenser elements of each section preferably have the same inside and outside diameters though, as has been pointed out above and as will be clear from Figure 1 of the drawings, the diameters progressively diminish to provide the varying spacing between the condenser stack 23 and the walls of the casing 10.

The sections 23^a, 23^b, etc. are connected in series by connections indicated at 35 and the lowermost and end terminal of the lowermost sections 23^a of the condenser stack 23 is grounded to the casing 10, by a conductor 36.

The remaining condenser stacks are likewise preferably sectionalized, the sections of the stack 24 being shown at 24^a, 24^b, 24^c, etc., and the sections of the condenser stack 27 being indicated at 27^a, 27^b, 27^c, etc. The sections of the individual stacks are preferably connected in series.

A conductor 37, passing through the supporting tube 20 connects the uppermost and end terminal of the section 23^b with the uppermost and end terminal of the upper section 24^a of the stack 24 while a conductor 38, passing through the insulating tube 19, connects the lowermost section 24^c of the stack 24 to the lowermost section 27^a of the stack 27, a conductor 39, passing through the supporting tube 18, connecting the uppermost section 27^c of the stack 27 to the conductor that passes through the high voltage terminal, the latter permitting the connection of the condenser to a suitable circuit.

Inasmuch as the effective diameters and hence plate areas of the plates diminish as one passes from the outermost annular stack to the innermost or central stack, the number of sections in the inner condenser stacks diminishes since more individual condenser elements are required to make up each section, if the capacities of the various sections are to be maintained the same. It is also to be noted that I prefer to separate adjacent sections by suitable washers 40 of solid dielectric material.

The casing 10 is thereupon filled with a gaseous dielectric, such as nitrogen, under a pressure on the order of fifteen atmospheres, and this gaseous dielectric, having an exceedingly high dielectric strength, coats

with certain of the features above described in a unique manner to achieve many thoroughly practical advantages. In order that certain of these advantages may be better understood, it might first be pointed out that the various spacings, each preferably varying in width, as above described, are filled with this gaseous dielectric under pressure. It should further be noted that the condenser sections, serially connected as above pointed out, are connected, moreover, in a predetermined relation with respect to these varying spaces.

Considering first the spacing between the interior walls of the casing 10 and the condenser stack 23, it will first be noted, referring especially to the left-hand portion of Figure 1, that the spacing between the wall of the casing and the lowermost section 23^a, one of whose terminals is grounded to the tank, may be made relatively small, this spacing being filled with the gaseous dielectric under pressure which thus serves to effectively insulate these parts from each other. As the circuit is traversed in an upward direction along the coil sections 23^a, 23^b, 23^c, etc., assuming, of course, that the apparatus is connected to a suitable circuit, particularly one of high voltage, the voltage increases, each section adding to the voltage by an amount equal to the reactance drop therethrough. The voltage gradient, therefore, between the condenser stack 23 and the interior walls of the casing 10 increases, achieving a maximum between the uppermost section 23^b and the wall of the casing. The voltage difference might vary from substantially zero between the lowermost condenser section 23^a and the casing 10 to 5000 volts between the uppermost condenser section 23^b and the wall of the casing, assuming, by way of illustration, that the condenser is to operate upon a 15000-volt circuit and that each stack is to provide a reactance drop of 5000 volts. This varying potential difference is effectively insulated by the gaseous dielectric layer interposed between the outer stack 23 and the wall of the casing 10, the thickness of this layer increasing as the potential difference increases. Due to the high dielectric strength of the gaseous dielectric under pressure I am enabled to much more closely space these two parts than would otherwise be the case.

The stack 23 is insulated from the stack 24 by the solid dielectric sleeve 20 and a layer of gaseous dielectric under pressure arranged in series with the solid dielectric of the sleeve, the thickness of the gaseous dielectric layer increasing with the increase in potential difference between adjacent parts or sections of the two stacks. This spacing is greatest between the lowermost sections 23^a and 24^a, since the voltage difference between any parts of the two stacks is

greatest here. In a substantially similar manner the stacks 24 and 27 are insulated from each other until the highest potential, above assumed to be 15000 volts, is reached at the terminal of the uppermost section 27^c of that stack that is most remote from the walls of the casing. The location of the high voltage terminal 13, moreover, is also such that the high tension lead 39 can be very short and need not take any circuitous path.

By reason of the coaction of the gaseous dielectric under pressure with the solid dielectric material, these two dielectrics being arranged in series between adjacent stacks, I am enabled to much more closely position adjacent stacks than would otherwise be the case and I am also enabled to use a much lesser thickness and hence weight of solid dielectric material. Assuming the solid dielectric tubular supports to be made of bakelite, for example, these parts will then have a permittivity of about 5 or 6, while the permittivity of the gaseous dielectric under pressure is substantially unity. The dielectric stress, in a radial direction, between any two parts of adjacent stacks, for example, between the sections 23^b and 24^a of the stacks 23 and 24, will be divided between the solid dielectric material of the tube 20 and the layer of gaseous dielectric under pressure inversely as the permittivities of the two serially arranged dielectrics. The solid dielectric will assume one-sixth or one-seventh of the total stress while the gaseous dielectric under pressure, having such a high dielectric strength, will assume five-sixths or six-sevenths of the total stress, assuming equal thicknesses of the two dielectrics.

As the potential differences between adjacent condenser stacks increase, the layer of gaseous dielectric increases in thickness and thus I achieve graded insulation without necessitating peculiarly shaped solid insulating barriers.

Bearing in mind that the capacities of the various condenser units or elements is a function of the square of their diameters, it will be seen that, for a given size of cylindrical tank, I am enabled to encompass therein a condenser construction of high capacity, due to the possibility of closely spacing the parts as above described. Furthermore, in connecting the condenser stacks so that those of higher or highest potential are increasingly more distant from the cylindrical walls of the container 10, I am enabled greatly to minimize the difficulties of insulation for the high voltages at which this type of apparatus may function, not only reducing the expense of construction in making it possible to eliminate cumbersome insulating supports but also in avoiding the waste of effective space for such

cumbersome solid dielectric supporting means.

It will thus be seen that there has been provided in this invention a condenser construction in which the various objects hereinbefore noted, as well as many thoroughly practical advantages are successfully achieved. It will be seen that the apparatus is of simple and durable construction and is exceedingly well adapted for operation at high voltages, achieving, moreover, a high capacity per unit volume and otherwise a high efficiency of action.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In condenser construction, in combination, a closed container of circular cross-section, a plurality of substantially concentrically arranged torus-shaped condenser stacks within said container having their axes substantially coincident with the axis of said container, an end terminal of the outermost stack being maintained at substantially the same potential as said container, means connecting said stacks in series so that the potential of the latter increases in a direction from the outermost stack to the innermost stack, and means including solid dielectric material and a gaseous dielectric under pressure arranged in series therewith for insulating one stack from another.

2. In condenser construction, in combination, a closed container of circular cross-section, a plurality of substantially concentrically arranged torus-shaped condenser stacks within said container having their axes substantially coincident with the axis of said container, an end terminal of the outermost stack being maintained at substantially the same potential as said container, means connecting said stacks in series so that the potential of the latter increases in a direction from the outermost stack to the innermost stack, said stacks being shaped to provide spaces intervening therebetween which spaces increase as the voltage between adjacent spaced stacks increases, and a dielectric medium filling said spaces.

3. In condenser construction, in combination, a closed container of circular cross-section, a plurality of substantially concentrically arranged torus-shaped condenser stacks within said container having their axes substantially coincident with the axis of said container, an end terminal of the outermost stack being maintained at sub-

stantially the same potential as said container, means connecting said stacks in series so that the potential of the latter increases in a direction from the outermost stack to the innermost stack, said stacks being shaped to provide spaces intervening therebetween which spaces increase as the voltage between adjacent spaced stacks increases, and means including a layer of solid dielectric material and a layer of gaseous dielectric under pressure in said spaces.

4. In condenser construction, in combination, a closed container of circular cross-section, a plurality of substantially concentrically arranged torus-shaped condenser stacks within said container having their axes substantially coincident with the axis of said container, an end terminal of the outermost stack being maintained at substantially the same potential as said container, means connecting said stacks in series so that the potential of the latter increases in a direction from the outermost stack to the innermost stack, said stacks being shaped to provide spaces intervening therebetween which spaces increase as the voltage between adjacent spaced stacks increases, and a gaseous dielectric under pressure in said spaces of increasing width.

5. In condenser construction, in combination, a closed container of circular cross-section, a plurality of substantially concentrically arranged torus-shaped condenser stacks within said container having their axes substantially coincident with the axis of said container, an end terminal of the outermost stack being maintained at substantially the same potential as said container, means connecting said stacks in series so that the potential of the latter increases in a direction from the outermost stack to the innermost stack, said outermost stack being spaced from the walls of said container by a space that increases in radial width as the voltage between said container and said stack increases, and a dielectric medium in said space.

6. In condenser construction, in combination, a closed container of circular cross-section, a plurality of substantially concentrically arranged torus-shaped condenser stacks within said container having their axes substantially coincident with the axis of said container, an end terminal of the outermost stack being maintained at substantially the same potential as said container, means connecting said stacks in series so that the potential of the latter increases in a direction from the outermost stack to the innermost stack, said outermost stack being spaced from the walls of said container by a space that increases in radial width as the voltage between said container and said stack increases, and a gase-

ous dielectric under pressure in said increasing space.

7. In condenser construction, in combination, a container of circular cross-section, a condenser stack within said container having substantially circular plate members and positioned so that its axis is substantially coincident with the axis of said container, a condenser stack of annular shape surrounding said first-mentioned stack and spaced from the latter and from the walls of said container, and means connecting said stacks so that a terminal of the second-mentioned stack is at substantially the same potential as said container and a terminal of said first-mentioned stack is at the highest operative potential of the apparatus.

8. In condenser construction, in combination, a container of circular cross-section, a condenser stack within said container having substantially circular plate members and positioned so that its axis is substantially coincident with the axis of said container, and a condenser stack of annular shape surrounding said first-mentioned stack and spaced from the latter and from the walls of said container, the spacing between the walls of said container and said second-mentioned stack increasing as the voltage therebetween increases.

9. In condenser construction, in combination, a container of circular cross-section, a condenser stack within said container having substantially circular plate members and positioned so that its axis is substantially coincident with the axis of said container, a condenser stack of annular shape surrounding said first-mentioned stack and spaced from the latter and from the walls of said container, and means including a solid dielectric material and a gaseous dielectric under pressure arranged in series therewith for insulating one stack from the other.

10. In condenser construction, in combination, a container of circular cross-section, a condenser stack within said container having substantially circular plate members and positioned so that its axis is substantially coincident with the axis of said container, and a condenser stack of annular shape surrounding said first-mentioned stack and spaced from the latter and from the walls of said container, the spacing between said two condenser stacks increasing as the voltage therebetween increases.

11. In condenser construction, in combination, a container of circular cross-section, a condenser stack within said container having substantially circular plate members and positioned so that its axis is substantially coincident with the axis of said container, a condenser stack of annular shape surrounding said first-mentioned stack and spaced from the latter and from the walls of said container, the spacing between the walls of

said container and said second-mentioned stack increasing as the voltage therebetween increases, and a gaseous dielectric under pressure in said increasing space.

12. In condenser construction, in combination, a container of circular cross-section, a condenser stack within said container having substantially circular plate members and positioned so that its axis is substantially coincident with the axis of said container, a condenser stack of annular shape surrounding said first-mentioned stack and spaced from the latter and from the walls of said container, the spacing between said two condenser stacks increasing as the voltage therebetween increases, and means including a gaseous dielectric under pressure in said increasing space.

13. In condenser construction, in combination, a container of circular cross-section, a condenser stack within said container having substantially circular plate members and positioned so that its axis is substantially coincident with the axis of said container, a condenser stack of annular shape surrounding said first-mentioned stack and spaced from the latter and from the walls of said container, one of said spacings containing a solid dielectric material and a gaseous dielectric under pressure arranged in series therewith.

14. In condenser construction, in combination, a container, a plurality of tubular members of solid dielectric material, each of different diameter, means supporting said tubular members concentrically within said container, and washer-shaped condenser plates held in spaced relation and strung onto said tubular member.

15. In condenser construction, in combination, a container, a plurality of tubular members of solid dielectric material, each of different diameter, means supporting said tubular members concentrically within said container, and washer-shaped condenser plates held in spaced relation and strung onto said tubular member, the outside diameters of the washer-shaped plates strung on one of said tubular members varying substantially progressively in diameter.

16. In condenser construction, in combination, a container of circular cross-section, a condenser stack having substantially circular plates and having its axis substantially coincident with the axis of said container, a plurality of torus-shaped condenser stacks about said first-mentioned stack and interposed therebetween and the walls of said container, and means connecting said stacks so that the potential between any one stack and the container increases with the increase in spacing of the stacks from the walls of said container.

17. In condenser construction, in combination, a casing, a condenser stack substan-

tially centrally positioned therein, and a condenser stack interposed between said first-mentioned stack and the walls of said container and having plates shaped to extend 5 completely about said central stack.

18. In condenser construction, in combination, a casing, a condenser stack substantially centrally positioned therein, a condenser stack interposed between said first-
10 mentioned stack and the walls of said container and having plates shaped to extend completely about said central stack, said second-mentioned stack being spaced from both said container and said central stack,
15 and an insulating medium filling the spaces therebetween.

19. In condenser construction, in combination, a casing, a condenser stack substantially centrally positioned therein, a condenser stack interposed between said first-mentioned stack and the walls of said container and having plates shaped to extend completely about said central stack, said second-mentioned stack being spaced from
25 both said container and said central stack, and a layer of solid dielectric material and a layer of gaseous dielectric under pressure in series therewith in one of said spacings.

20. In condenser construction, in combination, a casing, a condenser stack substantially centrally positioned therein, a condenser stack interposed between said first-mentioned stack and the walls of said container and having plates shaped to extend completely about said central stack, and means
25 connecting said stacks so that the potential between said first-mentioned stack and said container is greater than the potential between said second-mentioned stack and said
40 container.

In testimony whereof, I have signed my name to this specification this 22nd day of March, 1930.

RAYMOND A. LANE.
